UNITED STATES PATENT OFFICE.

CARMINE TARTAGLIA OF ALBUQUERQUE, NEW MEXICO.

MUSIC-LEAF TURNER.

Application filed July 16, 1923. Serial No. 651,786.

This invention relates to certain new and useful improvements in music leaf turners, and especially that class of such devices in which the turning arms are operated by

improvements in their useful applications to the particular constructions, which for the purpose of explanation have been made the 55 subject of illustration.

5 spring or elastic means.

In the drawings:

One of the objects of my invention is to furnish a device which may be attached to a piano, organ, or other instrument and operated conveniently by the performer 10 through a slight pressure of his foot upon a pedal.

Figure 1 is a side elevation of a piano, showing my improved device attached thereto.

Another object of my invention is to so construct my device that it may be readily adapted to a music stand or other music 15 support, not connected with an instrument.

Fig. 2 is a similar side elevation of my improved device attached to a telescopic music stand.

A further object of my invention is to provide a device, whose construction is simple and durable and not likely to get out of order or become disarranged.

Fig. 3 is an enlarged front view of my device at it appears without the music book 65 thereon.

20 My improved device consists of a base mounted, for instance, above the key board of a piano, upon which is preferably a metallic rest bent slightly outwardly from a vertical central line, the lower edge of the rest being turned upwardly at an angle to the body so as to afford a support or rest for the music book. A suitable binding rod or narrow plate is positioned vertically down the center line of the book, so as to hold it in 25 proper position and from an upper support extend lateral arms adapted to turn the sheets of music. These arms are mounted in a horizontal plane substantially parallel to the upper edges of the leaves and by suitable 30 mechanism adapted to be operated by the foot of the musician, turn the leaves from their initial position at the right side of the rest to the left side thereof.

Fig. 4 is a front view showing the book mounted upon the rest, and the manner of securing the leaves to the turning or carrying 70 arms.

With these and other objects in view, 35 which may be incident to my improvement, the invention consists in the parts and combinations to be hereinafter set forth and claimed, with the understanding that the several necessary elements comprising my 40 invention, may be varied in construction, proportions and arrangement, without departing from the spirit and scope of the appended claims.

Fig. 5 is a detail view of part of the leaf carrying arms, showing the manner of supporting the leaf upon the arm.

In order to make my invention more clearly 45 understood, I have shown in the accompanying drawings, means for carrying the same into practical effect, without limiting the

Fig. 6 is an enlarged section on the line 6—6 of Fig. 4.

Fig. 7 is an enlarged detail section on the line 7—7 of Fig. 4.

Fig. 8 is a perspective view of the music book, as prepared for use with the carrying arms.

Fig. 9 is a general plan view of my device.

Fig. 10 is a horizontal sectional view on the line 10—10 of Fig. 3.

Fig. 11 is a detail side elevation of my device, minus the foot pedal.

Fig. 12 is a perspective view of the binding rod showing only one of the leaf-carrying arms.

Fig. 13 is an enlarged detail side elevation of the mechanism for retaining and releasing the leaf-carrying arms.

Fig. 14 is a front view of the same.

Fig. 15 is a horizontal vertical sectional view of the mechanism shown in Figs. 13 and 14, and

Fig. 16 is a section on the line 16—16 of Fig. 13, showing the yoke for feeding out the leaf carrying arms.

Like reference characters indicate the same or corresponding parts throughout the 100 several views of the drawing.

The numeral 1 refers to a piano or organ, upon which in any suitable manner is mounted a base-board 2. Fastened to the

base-board, as clearly shown in Fig. 10, are short rods 3 3' 3'', extending from plates 4, 4 4', said plates being secured to the base-board by any appropriate means. The bar 3' is slightly longer than the others and terminates in a hook 5. These bars support the music rest 6, which is made preferably of metal and bent slightly outwardly from its central vertical line. The lower edge 7 thereof is upturned so as to provide a supporting shelf 8 for the music book, which shelf at its center 9 is slightly cut away so as to permit of the lower end of the binding rod 10 being embraced by the hook 5.

For the purpose of illustration, I have, in Fig. 12, shown my device with one only of the turning or leaf carrying arms attached. The drawing shows the plate 4' with its attached rod 3' at a point below the music rest, and higher up in the same vertical plane is another plate 12 secured to the base board extending from which is a rod 13 with a cross head 14 in which is mounted an upwardly extending small rod 15, having upon its upper end a plate or nut 16, with an attached curved guide 17. Upon this rod 15 are mounted the angular ends of the turning arms. The top of the vertical bar 10 is provided with an eye 10' which fits within the ring 14' depending from the bottom of the cross head.

The purpose of the rod 15 is to support a series of carrying or turning arms 23, which pivot thereon. Each of these arms is stamped out of sheet metal and consists of an upper member or shank 23 and a lower member 24, the upper member being longer than the lower, and provided near its outer end with a snap hook 25, the lower end member is resilient and is adapted to be sprung into hook 25.

It will also be noted, as seen more particularly in Figs. 3, 4 and 5, that each upper member 23 is provided with an ear 27. The inner end of this member 23 is bent upwardly for a short distance, is then again bent at right angles to the body and in an opposite direction, and is apertured, so as to fit over and turn upon the rod 15. The left side of the base board is provided with another rod 28 having a hook 29, to which is attached one end of a series of elastic bands 31, the free ends of which extend across the guide 17, and are each fastened to one of the series of turning arms. As soon as one of said arms becomes free to move, as will later appear, the elasticity of the band imparts momentum to said turning arm and swings it from its position of rest on the left side over and off the guide 17 to a position of rest on the right side. The points of the attachment of the elastic bands are such that the drag upon the leaf carrying arms would be exerted in practically the same plane. The guide 17 is therefore provided and located

at a point nearer the key board, so as to enable the bands to respond quickly in action, as promptness in turning the leaves is very desirable.

Fig. 4 shows a music book in place upon the music rest. Each of its pages near the upper edge carries three grommets 35, each provided beyond the edge with an eye 36, through which eyelets the lower member 24 of the turning arm passes, as more clearly appears in the detail views Nos. 4, 5, 6 and 7.

Upon the upper part of the base-board and to one side thereof is secured by a bolt 40 a horizontally extending block of wood or metal 41, whose outer end terminates in a downwardly extending nose 42. Also secured upon the base-board immediately beneath the block 41 and helping to sustain the same is a block 43. This block, as shown in Figs. 15 and 16 is drilled through at the bottom and top to allow the passage of the rods 45 and 46 whose base is secured in the metal plate 47 from which the horizontal rods 45 and 46 extend. Each of these rods carries a spiral spring 52 and 53, which yieldingly push forward a follow plate 48 which is provided with guide openings 49 and 50, through which the rods 45 and 46 extend.

Mounted upon the upper part of the block 41 is secured by screws or otherwise a plate 55, provided with ears 56 in which is pivotally mounted a curved presser bar 57. One end of this bar is flattened as at 58 and provided with a slot 59, in which is a pin 61 carried by a yoke 61', the pin resting upon one end of a resisting spiral spring 62. The other end of this presser bar is provided with an eye 63, to which is attached one end of a cable 64. This cable is trained over a pulley 65 carried by a bracket 66 mounted on the base-board. The cable 64 may also be trained over the other pulleys, when my device is attached to a piano, such as seen in Fig. 1, or to a music stand, as seen in Fig. 2, its free end being attached to a foot pedal 67, which is operated by the musician.

The yoke 61' is mounted in guide channels 68 secured by screws or in any convenient manner to the opposite sides of the block 41, and when the foot pedal is depressed, the end 58 of the bar moves downwardly, causing the end 62' of said bar to depress one of the turning or carrying bars against the upward pressure of the top or finger 70 of the spring 71, until it becomes released, whereupon, under the action of one of the elastic bands 31, said bar swings from the right side to the left carrying with it the page of music attached thereto, without requiring the use of the hand of the musician.

While I have shown and described the preferred embodiment of my invention, I wish it to be understood that I do not confine

myself to the precise details of construction hereinbefore set forth, by way of illustration, as it is apparent that many changes and variations may be made therein by those skilled in the art, without departing from the spirit of the invention, or exceeding the scope of the appended claims.

I claim:—

1. In a music leaf turner for use with music leaves having eyelets thereon, a base-board, a rod mounted on the base-board, a bifurcated arm mounted upon the rod, a downwardly projecting hook on one of the arm sections, the other arm section adapted to be engaged by the hook and adapted to engage the eyelets on the music leaves, and a downwardly projecting finger at the free end of the arm.
2. In a music leaf turner a plurality of pivoted bifurcated arms, a hook for securing the bifurcations of each arm together, one of the bifurcations of each arm engaging eyelets on a leaf of music, a curved guide above said arms, elastic members secured to each of the arms and a stationary hook and passing over the curved guide, a stop mechanism engaging the free end of each bifurcated arm, and a pressure member to release the arms consecutively.
3. In a music leaf turner for use with music leaves having eyelets thereon, a base board, a rod mounted on the base-board

a plurality of turning arms pivotally mounted upon the rod, each arm comprising a shank, a bifurcated arm integral with the shank, a hook carried by one of the bifurcations adapted to engage the free end of the other bifurcations, one of the arms being longer than the other and provided with a downwardly projecting finger on the free end thereof.

4. In a music leaf turner for use with music leaves having eyelets thereon, a bracket, a plurality of turning arms pivotally mounted upon said bracket, each turning arm comprising a shank having an integral arm, a spring attaching ear upon the arm, a downwardly directed hook carried by the arm, a downward projection upon the free end of the arm engaging a releasing mechanism, and a stem integral with the arm adapted to be received and held in close position by said hook and to engage the eyelets on the music leaves.

5. In a music leaf turner for use with music leaves having eyelets thereon, a base-board supporting a rod, a spring-actuated arm pivotally mounted upon said rod and having a hook and stem thereon, said stem adapted to engage eyelets on the music leaves and be held in a closed position by said hook.

In testimony whereof I affix my signature.
CARMINE TARTAGLIA.
